The ornamental design for a supportive apparel, as shown and described.

DESCRIPTION

FIG. 1 is a front perspective view of a supportive apparel showing my new design.

FIG. 2 is a rear elevation view of the supportive apparel of FIG. 1; and,

FIG. 3 is a side elevation view of the supportive apparel of FIG. 1, turned inside-out.

The broken lines shown on the inner and outer rear surfaces of the waistband are stitching and form a part of the claimed design.

The stippling in the drawings represents texture.
